(57) **CLAIM**

The ornamental design for a mopping cloth for cleaning robot, as shown and described.

DESCRIPTION

1.1 is a front view of a first embodiment of a mopping cloth for cleaning robot, showing the new design;

1.2 is a rear view thereof;

1.3 is a left view thereof;

1.4 is a right view thereof;

1.5 is a top view thereof;

1.6 is a bottom view thereof;

1.7 is a front perspective view thereof;

1.8 is a rear perspective view thereof;

3.1 is a front view of a second embodiment of a mopping cloth for cleaning robot, showing the new design;

3.2 is a view thereof;

3.3 is a left view thereof;

3.4 is a right view thereof;

3.5 is a top view thereof;

3.6 is a bottom view thereof;

3.7 is a front perspective view thereof; and

3.8 is a rear perspective view thereof.
